UNITED STATES PATENT OFFICE.

ALFRED C. NELSON, OF CLEVELAND, OHIO, ASSIGNOR OF ONE-HALF TO ARTHUR G. MCKEE,
OF CLEVELAND, OHIO.

REGENERATIVE STOVE.

No. 925,827.

Specification of Letters Patent. Patented June 22, 1909.

Application filed January 16, 1909. Serial No. 472,659.

To all whom it may concern:

Be it known that I, ALFRED C. NELSON, a citizen of the United States, resident of Cleveland, county of Cuyahoga, and State of Ohio, have invented a new and useful Improvement in Regenerative Stoves, of which the following is a specification; the principle of the invention being herein explained and the best mode in which I have contemplated applying that principle, so as to distinguish it from other inventions.

My invention relates to regenerative stoves such as are used in blast furnace practice and in whose construction bricks enter largely. The object of my invention is to construct a stove of the above-described character in a manner such that bricks of standard size and simplicity of form may be used to the greatest possible extent and at the same time impart to the structure the preferred circular exterior outline of its horizontal section and the preferred circular cross section of the central combustion chamber thereof, together with the required interior heating surface of the checkerwork.

Heretofore, in so far as I am aware, the ordinary construction of regenerative stoves has involved the use of special bricks in the construction of the exterior inclosing brick shell, the interior shell forming the combustion chamber, and the checkerwork. These special bricks are laid in circular courses to form the required vertical walls. Inasmuch as each circular course in the same plane has a different diameter, the form of brick for each such course has necessarily been different from that of each of the other courses in said plane. This necessitated the use of forms of brick which are not standard in shape and which are classified as what is known in the trade as "special" brick. In view of the special character of these brick, an increased expense is involved in the construction of this class of stoves. Special brick for forming the radial walls crossing the circular walls are also required. The great majority of the brick, therefore, in this class of stoves, are of special form and considerable additional expense is involved in their use, as compared with such brick structures as may be built out of standard rectangular brick and standard tapered brick.

The standard rectangular brick is substantially 9 inches long by $4\frac{1}{2}$ inches wide by $2\frac{1}{2}$ inches thick, and the standard tapered brick

is 9 inches long, $4\frac{1}{2}$ inches wide at one end, $2\frac{1}{2}$ inches thick at the same end and the width or thickness of the other end or both width and thickness of such end may be less than $4\frac{1}{2}$ and $2\frac{1}{2}$ inches respectively, according to standards well known to the brick trade furnishing materials for this class of work, also well known to those skilled in the art of constructing blast furnace stoves.

My invention contemplates the use of a larger per cent. of standard brick in the construction of a regenerative stove than it has heretofore been possible to use in this character of devices and the said invention consists of a certain form of structure, and details thereof as hereinafter fully described and specifically set forth in the claims.

The annexed drawings and the following description set forth in detail a certain structure embodying my invention, the disclosed structure, however, constituting but one of various forms in which the principle of the invention may be used.

In said annexed drawings: Figure 1 is a vertical axial section of a regenerative stove constructed in accordance with my invention. Fig. 2 is a fragmentary axial section of such stove taken upon the plane indicated by line II—II in Fig. 4. Fig. 3 is a similar fragmentary section taken upon the plane indicated by line III—III in Fig. 4. Fig. 4 is a horizontal section, upon an enlarged scale, of the stove, taken upon the plane indicated by lines IV—IV in Fig. 1, said planes passing immediately above the lowermost course of brick of the checkerwork which lies immediately above the crown of the arches, and immediately below such course, the bricks lying immediately upon the arches being shown partially removed to disclose part of the latter in plan. Fig. 5 is a horizontal section taken upon the plane indicated by line V—V in Fig. 1. Fig. 6 is a fragmentary horizontal section taken upon the plane indicated by line VI—VI in Fig. 1, this plane passing through the middle of one course of brick. Fig. 7 is a similar fragmentary section taken upon a plane indicated by line VII—VII parallel with that indicated by line VI—VI but a distance below same equal to the distance from center to center of two successive courses. Fig. 8 is a fragmentary plan, viewed from the plane indicated by line VIII—VIII, Figs. 10 and 11, upon an enlarged scale, of two courses of brick. Fig. 9

is a similar view taken upon the plane indicated by line IX—IX; Figs. 10 and 11, such latter courses lying immediately above those shown in Fig. 8. Fig. 10 is a fragmentary 5 vertical section, upon the scale employed in Figs. 4, 5, 6 and 7, and taken upon the plane indicated by line X—X, Fig. 9. Fig. 11 is a similar fragmentary section taken upon the plane indicated by line XI—XI in Fig. 9. 10 Fig. 12 is a perspective view upon an enlarged scale of the four fragments, indicated by lines y , y' , y^2 and y^3 , Figs. 8 and 9, of checkerwork which occur successively one upon the other to form the four walls of one 15 of the flues, these fragments being shown vertically detached from each other in order to disclose the vertical relation of the component bricks thereof.

The central combustion chamber A is of 20 the usual cylindrical form and the lower portion thereof is lined with the usual brick a of extremely high refractory qualities, this lining being, as is well known, located in the region of greatest heat. Next to the lining 25 composed of the bricks a and of similar refractory character is the usual lining a' extending to the top of the checkerwork and formed out of standard tapered and straight brick. This lining a' extends to the bottom 30 of the stove. The linings a and a' constitute the central shell forming the vertical combustion chamber. Surrounding this shell of the combustion chamber is a brickwork structure B, the bricks of which are laid 35 parallel with and at right angles to a given plane such as x — x , Fig. 4, passing through the axis of the combustion chamber. These bricks are all of standard rectangular form and those lying adjacent to the outer surface of 40 the shell of the combustion chamber are suitably chipped away to properly fit against same in the usual manner. The bricks in the courses forming this structure are laid alternately parallel with and at right angles to 45 the said plane whereby the component bricks are caused to break joint and thereby bond such courses. Certain courses, preferably every seventh, are caused to intersect the courses of lining a' , as shown in dotted 50 lines in Fig. 4, thus bonding the shell and the brickwork structure B. These courses are caused to terminate outwardly so as to impart to the horizontal section of this inner inclosing structure a substantially rectangular outline, as shown in Figs. 4, 5, 6 and 7.

The outer inclosing structure C is formed 55 of courses of standard brick also laid alternately parallel with and at right angles to the above named plane, as shown in Fig. 4, and 60 the outermost bricks of these courses are suitably chipped to impart to the horizontal section of this outer inclosing structure a circular outline. The usual steel inclosing shell D surrounds the brick structure C; as 65 shown.

Having their inner and outer ends embedded respectively in the structures B and C are two sets of arches E', E², F', F², Fig. 4, the one set being parallel with the aforesigned plane and composed of two groups, 70 the component members of which are equal in number, parallel with each other and disposed upon opposite sides of the structure B. The other set of arches consists similarly of arches disposed equally upon opposite sides 75 of the structure B, the component members of which are parallel with each other but which are placed at right angles to the above-named plane. These arches project perpendicularly from the respective sides of 80 the structure B in which their inner ends are embedded, as shown. The distance between the arches of each group is made 9 inches, that is, equal to the length of a standard rectangular brick. Brickwork is built 85 up on each arch so as to bring a course terminating in a plane tangent to the crown of the arch. Laid transversely across the top of these courses of each group of arches are 13 $\frac{1}{2}$ x 6 x 2 $\frac{1}{2}$ inch brick g forming parallel rows 90 inches from each other, and at right angles to said arches. These rows of brick g form foundations for vertical walls G which are built upwardly and vertically and which cross vertical walls F built upon and in 95 alinement with the arches and therefore at right angles to walls G. These walls G and F form the checkerwork of the stove. The courses of bricks of walls G of this checkerwork are laid in a manner such as to make 100 each course bond the contiguous upper and lower course, so that no two successive courses contain seams in the same vertical plane. This I accomplish by laying first the bricks of one course in parallel rows end to 105 end to form part of a wall G, as shown in the lower course in dotted lines in Fig. 8. These bricks are all of standard dimensions, 9 inches in length, and between these rows and spaced 9 inches apart are transversely laid 110 similar standard 9 inch bricks which I shall hereinafter refer to as filler brick, to form part of the wall F. The next course above, shown in full lines in Fig. 8 is made by laying 115 parallel rows of bricks end to end but at right angles to the parallel rows of the lower course, to continue the wall F. Between the parallel rows of this upper course are filler bricks spaced 9 inches apart as shown in full 120 lines in Fig. 8, to continue the wall G. The next course above is arranged in a manner similar to that of the lower course shown in dotted lines in Fig. 8, as is shown in dotted lines in Fig. 9. The rows of bricks of this last described course which are laid end to 125 end run in the same direction as those laid end to end in the first described course, but they are so placed as to break joint vertically with the bricks of said first described course. The next course above the third described 130

course is shown in full lines in Fig. 9 and consists of parallel rows of bricks laid end to end running at right angles to the parallel rows shown in the third described course, standard 9 inch filler brick being laid across between these rows as before, resembling the arrangement of the second described course. The bricks in this last described course are so laid as to break joint with the course immediately below it, as shown in Fig. 9, and therefore also break joint, as shown, with the bricks of the second described course. It will hence be seen that the four courses of bricks contain no seams located in the same vertical planes with the exception of the fillers, which break joint in every other course. In this manner these courses are effectively bonded and danger from cracking along a line of least resistance and of any considerable length is therefore reduced to a minimum. The construction of the courses as just described is repeated in the checkerwork indefinitely and the relation of the bricks of the four courses is clearly illustrated in Fig. 12, the bricks in this figure being shown in the positions which they occupy relatively to each other in horizontal planes.

It is obvious that a combination of the first and second described courses may be used throughout, or a combination of the third and fourth, in each case providing a completely bonded structure, having the advantages desired to a some what limited degree, and which may be found to suffice in some cases. In this event, however, every other course will have vertically alined joints, whereas by using the combination of the four courses each constructed as previously described, such alined joints occur only in every fourth course, with the exception noted above.

In order to impart to the annular cross section of the checkerwork a substantially uniform width so as to obtain a substantially uniform area of checkerwork in all vertical axial planes of the stove, I provide additional flues as follows: The end arches of each group are made to terminate respectively in planes coincident with the sides of the brickwork B from which they project. This arrangement causes the adjacent end arches of successive groups to cross each other as at f, Fig. 4. Beneath this crossing point is placed a brick pillar B', Figs. 2 and 4, and the brickwork B is corbeled as at b, Figs. 2 and 5, from both sides of the brickwork so as to meet at the top of the pillar B'. The corbeling and the pillar therefore form the inner support for the crossed arches. An additional flue H may therefore be provided at each corner whose outermost walls are supported by the inner ends of the crossed arches. These flues form recesses in the corners of the brick structure B and their outer walls are in

the same vertical planes with the adjacent walls of said brickwork. Radially opposite each flue H is a flue H' whose inner walls h h, Fig. 4, are supported independently of the arches by means of corbeling as at h', Figs. 2 and 5. It will be noted that the bottoms of the flues H H' are both above the floor of the stove and communicate with the annular space J formed beneath the arches. This annular space therefore has the required sectional area necessary for the passage of the gases and the required uniformity of checkerwork area is obtained. A substantially uniform distribution of checkerwork is therefore obtained in all vertical radial planes, as will be readily understood by those skilled in the art. The location of the additional flues H and H' with reference to each other and in a horizontal plane is shown in dotted lines in Fig. 5, as is also the location of the corbeling b and h.

The usual hot blast valve duct M, gas duct M', chimney duct M², air relief duct M³ and cleaning ducts m m are provided, as shown in Fig. 5, communicating laterally with the interior of the lower part of the stove.

It will be obvious to those skilled in the art that the principles of checker construction above described may be applied to stoves known as "side combustion-chamber" stoves.

What I claim therefore and desire to secure by Letters Patent is:—

1. In a regenerative stove, the combination of a central shell forming a vertical combustion chamber; brickwork surrounding said shell, the bricks of which are laid parallel with and at right angles to a given vertical plane; and forming a shell-surrounding structure of rectangular horizontal section; arches projecting at right angles from the sides of said shell-inclosing structure; vertical walls superimposed upon said arches, and forming vertical flues; and an outer shell of brickwork supporting the outer arch-ends.

2. In a regenerative stove, the combination of a central shell forming a vertical combustion chamber; brickwork surrounding said shell, the bricks of which are laid parallel with and at right angles to a given vertical plane, and forming a shell-surrounding structure having a rectangular horizontal section; four groups of arches projecting at right angles from the sides of said structure, the members of each group being parallel with each other; vertical walls superimposed upon and vertically alined with said arches; foundations transverse relatively to each group of arches and supported by the latter; vertical walls superimposed upon and vertically alined with said foundations; and an outer inclosing

shell of brickwork supporting the outer arch ends.

3. In a regenerative stove, the combination of an inner brickwork structure forming a combustion chamber; an outer inclosing brickwork structure in which the bricks in the courses are laid parallel with and at right angles to a given vertical plane; arches connecting said inner and outer structures; and checkerwork supported by said arches.

4. In a regenerative stove, the combination of an inner brickwork structure forming a combustion chamber and in which the bricks in the courses are laid parallel with and at right angles to a given vertical plane; an outer inclosing brickwork structure in which the bricks in the courses are also laid parallel with and at right angles to said plane; arches connecting said inner and outer structures; and checkerwork supported by said arches.

5. In a regenerative stove, the combination of an inner brickwork structure forming a combustion chamber; an outer inclosing brickwork structure in which the bricks in successive courses are laid alternately parallel with and at right angles to a given vertical plane; arches connecting said inner and outer structures; and checkerwork supported by said arches.

6. In a regenerative stove, the combination of an inner brickwork structure forming a combustion chamber and in which the bricks in successive courses are laid alternately parallel with and at right angles to a given vertical plane; an outer inclosing brickwork structure in which courses are also laid alternately parallel with and at right angles to said plane; arches connecting said inner and outer structures; and checkerwork supported by said arches.

7. In a regenerative stove, the combination of an inner brickwork structure forming a combustion chamber and in which the bricks in the courses are laid parallel with and at right angles to a given vertical plane; an outer inclosing brickwork structure in which the bricks in the courses are likewise laid parallel with and at right angles to said plane; arches connecting said two structures and placed parallel with and at right angles to said plane; and vertical walls supported by said arches and forming checkerwork, part of which walls are in vertical alinement with said arches.

8. In a regenerative stove, the combination of an inner brickwork structure forming a combustion chamber and in which the bricks in the courses are laid parallel with and at right angles to a given vertical plane; an outer inclosing brick structure in which the bricks in successive courses are laid alternately parallel with and at right angles to a given vertical plane; checkerwork built between said inner and outer structures and

said plane; arches connecting said two structures and placed parallel with and at right angles to said plane; and vertical walls supported by said arches and forming checkerwork, part of which walls are in vertical alinement with said arches.

9. In a regenerative stove, the combination of an inner brickwork structure forming a combustion chamber and in which the bricks in successive courses are laid alternately parallel with and at right angles to a given vertical plane; an outer inclosing brick structure in which the bricks in successive courses are likewise laid alternately parallel with and at right angles to said plane; arches connecting said two structures and placed parallel with and at right angles to said plane; and vertical walls supported by said arches and forming checkerwork, part of which walls are in vertical alinement with said arches.

10. In a regenerative stove, the combination of an inner brickwork structure forming a combustion chamber and in which the bricks of successive courses are laid parallel with and at right angles to a given vertical plane; an outer inclosing brickwork structure; arches connecting said two structures; and vertical walls supported by said arches and forming checkerwork; said outer structure being provided with additional checkerwork supported from below independently of said arches.

11. In a regenerative stove, the combination of an inner brickwork structure whose horizontal cross-section is of rectangular outline; an outer brickwork structure whose horizontal cross section is of circular outline; and vertical walls suitably supported intermediate of said structures to form vertical flues; each corner of said inner brickwork structure being recessed to form a vertical flue; that portion of the outer inclosing structure radially opposite said corners being formed with additional vertical flues.

12. In a regenerative stove, the combination of an inner brickwork structure having a horizontal cross-section of rectangular outline; an outer inclosing brickwork structure; two pairs of arches at right angles with each other, the members of each pair being parallel with each other, the inner ends of said arches being supported at one corner of said inner brickwork structure, two of said arches crossing each other; and a pillar vertically beneath the crossing portions of said last named two arches.

13. In a regenerative stove, the combination of an inner brickwork structure forming a combustion chamber; an outer inclosing brickwork structure in which the bricks are laid parallel with and at right angles to a given vertical plane; checkerwork built between said inner and outer structures and

having its bricks also laid parallel with and at right angles to said plane; and means for suitably supporting said checkerwork.

14. In a regenerative stove, the combination of an inner brickwork structure forming a combustion chamber and having its bricks laid parallel with and at right angles to a given vertical plane; an outer inclosing brickwork structure in which the bricks are 5 also laid parallel with and at right angles to said plane; checkerwork built between said inner and outer structures and having its bricks also laid parallel with and at right angles to said plane; and means for suitably 10 supporting said checkerwork.

15. In a regenerative stove, the combination of an inner brickwork structure forming a combustion chamber; an outer inclosing brickwork structure; checkerwork built between said inner and outer structures; and means for suitably supporting said checkerwork; the bricks of said inner and outer structures and of said checkerwork being laid in the same directions and bonded with 20 each other.

16. In a regenerative stove, the combination of an inner brickwork structure forming a combustion chamber; an outer inclosing brickwork structure; checkerwork built between said inner and outer structures; and arches for suitably supporting said checkerwork; the bricks of said inner and outer structures and of said checkerwork being laid parallel with and at right angles to a 30 given vertical plane.

17. In a regenerative stove structure, vertical checkerwork formed by vertical walls intersecting each other at right angles, the first course of the walls having bricks laid 40 end to end in parallel rows with fillers at right angles to the rows, the second course having bricks laid end to end in parallel rows in the same vertical planes with the fillers of the previous course with fillers above the 45 rows of the previous course, all bricks in successive courses breaking joint with each other.

18. In a regenerative stove structure, vertical walls forming checker work, an inside circular wall and an outside circular wall, 50 the bricks composing all of which are laid

parallel with and at right angles to a given vertical plane.

19. In a regenerative stove structure, vertical walls forming checker work, an inside circular wall and an outside circular wall, 55 the bricks composing all of which are laid parallel with and at right angles to a given vertical plane, and are bonded with each other.

20. In a regenerative stove structure, vertical walls forming checkerwork, and a circular wall surrounding same, the bricks composing both checkerwork and circular wall being laid parallel with and at right angles to a given vertical plane and bonded 60 with each other.

21. In a regenerative stove structure, vertical checkerwork formed by vertical walls intersecting each other at right angles, the first course of the walls having bricks laid 70 end to end in parallel rows with fillers at right angles to the rows, the second course having bricks laid end to end in parallel rows in the same vertical planes with the fillers of the previous course, with fillers 75 above the rows of the previous course.

22. In a regenerative stove for blast furnace, checkerwork formed by vertical walls intersecting each other at right angles, the first course of the walls having stretchers 80 running continuously in one direction and fillers in the direction at right angles thereto, the second course having stretchers running continuously in the direction at right angles to the said first-named stretchers, with fillers 85 between, the third course having stretchers and fillers in the same directions as the first course, but the stretchers breaking joints over the centers of the bricks of the first course, the fourth course having stretchers and fillers in the same direction as the second course, but the stretchers breaking joints with the bricks of the second course. 90

Signed by me, this 13th day of January, 1909.

ALFRED C. NELSON.
